DISPENSING CONTAINER FOR BEAUTICIAN'S ITEMS

J Parker Moser, 623½ S. Flower St., Inglewood, Calif.

Filed Sept. 12, 1960, Ser. No. 62,116

Term of patent 3½ years

(Cl. D52—2)

FIG. 1 is a perspective view, as seen from the dispensing end of a dispensing container for beautician's items showing my new design.

FIG. 2 is a perspective view thereof, as seen from the loading end.

FIG. 3 is a longitudinal sectional view, drawn to a smaller scale, of said dispensing container, with the lid in a raised position.

The undisclosed side of the dispensing container is substantially the same in appearance as the side shown.

I claim:

The ornamental design for a dispensing container for beautician's items, substantially as shown and described.
